UNITED STATES PATENT OFFICE.

THOMAS F. PRYOR, JR., OF NEWARK, NEW JERSEY.

DESIGN FOR A BACK FOR MIRRORS OR SIMILAR ARTICLES.

SPECIFICATION forming part of Design No. 36,424, dated July 14, 1903.

Application filed June 16, 1903. Serial No. 161,756. Term of patent 3½ years.

To all whom it may concern:

Be it known that I, THOMAS F. PRYOR, Jr., a citizen of the United States, residing at Newark, in the county of Essex and State of New Jersey, have invented a new and original Design for Backs of Mirrors or Similar Articles; and I do hereby declare the following to be a full, clear, and exact description of the invention, such as will enable others skilled in the art to which it appertains to make and use the same, reference being had to the accompanying drawing, which forms a part of this specification.

The single figure of the drawing illustrates

a back of a mirror or other article, which is 15 deemed sufficient to clearly illustrate my novel and ornamental design.

What I claim as new is—

The ornamental design for the back of a mirror or similar article, as shown.

In testimony that I claim the foregoing I have hereunto set my hand this 13th day of June, 1903.

THOMAS F. PRYOR, JR.
